UNITED STATES PATENT OFFICE.

JACOB FASNACHT, OF LUDELL, KANSAS, ASSIGNOR OF ONE-HALF TO
BENJAMIN M. TOBIAS, OF SAME PLACE.

VEHICLE-BRAKE.

SPECIFICATION forming part of Letters Patent No. 395,126, dated December 25, 1888.

Application filed October 13, 1888. Serial No. 288,013. (No model.)

To all whom it may concern:

Be it known that I, JACOB FASNACHT, a citizen of the United States, residing at Ludell, in the county of Rawlins and State of Kansas, 5 have invented certain new and useful Improvements in Vehicle-Brake Gears; and I do hereby declare the following to be a full, clear, and exact description of the invention, such as will enable others skilled in the art to which 10 it appertains to make and use the same.

This invention relates to brake-gears for vehicles; and it consists in the novel construction and combination of the parts hereinafter fully described and claimed, whereby the 15 brake-blocks are applied to the wheels, and whereby the wheels are prevented from leaving the blocks under the swaying action of the vehicle-springs.

In the drawings, Figure 1 is a side view of 20 a portion of a vehicle-body having the improved brake-gear applied to it. Fig. 2 is a plan view of the same from below.

A is the body of the vehicle.

B are the wheels, and a are the axles, provided with springs b, which springs, however, 25 may be dispensed with, as this invention is also applicable to vehicles which are not mounted upon springs.

C is the brake-shaft, having cranks c at its 30 ends, and D are the brake-blocks which press against the wheels.

E are the brake-shaft brackets, secured to the under side of the vehicle-body and provided with hooks e for the attachment of the 35 stay-rods.

F is a bell-crank lever pivoted on the pin f, projecting from the vehicle-body, and G is a foot-plate provided with the stem g and ratchet-teeth g' on the side of the said stem. 40 H is a double eye at the end of the stem, and h is a pin connecting said double eye to the long horizontal end of the bell-crank lever F.

I is a catch projecting from the body of the 45 vehicle for the ratchet-teeth g' to engage with.

J is a flat spring secured to the body A and bearing against the projection i of the bell-crank lever, so that the brake-blocks are always held clear of the wheels, except when

the foot-plate is forcibly pressed upon. A 50 spiral or other form of spring may be used instead of the flat spring shown, if desired.

K is a rod which is connected to the short vertical arm of the bell-crank lever by the pin k and to the arm L, projecting from the brake-shaft C, by the pin l.

M is a link pivoted to the center of the axle of the wheels, which are pressed upon by the brake-blocks, or the said link may be secured to any central portion of the vehicle to which 60 the axle is secured.

N are the stay-rods, which pass through holes m in link M and are provided with heads n, so that they may swivel freely in the holes 65 m of link M.

O are flat-sided projections upon the rods N near the swivel ends, so that the rods may be turned by an ordinary wrench. The other ends of rods N have screw-threaded portions n', which engage with correspondingly-screw-threaded holes o' in the loops o, which are passed over the hooks e on the brake-shaft brackets. The stays hold the wheels securely in contact with the brake-blocks, and the pressure is equalized on both sides of the vehicle by the pivotal attachment of the link M 75 to the center of the axle.

What I claim is—

1. In a vehicle-brake gear, the combination, 80 with the brake-shaft journaled in brackets secured to the vehicle-body and provided with a projecting arm, cranked ends, and brake-blocks for pressing against the wheels, of the bell-crank lever pivoted to the vehicle-body, a rod connecting the bell-crank lever with the 85 arm projecting from the brake-shaft, a spring for holding the brake-blocks off the wheels, and a foot-plate provided with a stem and pivoted to the said bell-crank lever, substantially as and for the purpose set forth.

2. In a vehicle-brake gear, the combination, 90 with the brake-shaft provided with the arm L, of the bell-crank lever pivoted to the vehicle-body and provided with the projection i, the flat spring bearing against the said projection, the foot-plate provided with a ratchet-toothed stem pivoted to the said bell-crank lever, a fixed catch for the ratchet-teeth to en- 95

gage with, and the rod pivoted to the short arm of the bell-crank lever and to the arm on the brake-shaft, substantially as set forth.

3. In a vehicle-brake gear, the combination,
5 with the brake-shaft provided with cranked ends and brake-blocks, of the brake-shaft brackets provided with hooks, a link pivoted to the middle of the vehicle-axle, the revolu-
10 ble rods swiveled at one end in the said link
and having their other ends screw-threaded, and the loops engaging with the hooks on the

15 said brackets and having screw-threaded holes for the screw-threaded rod ends to en-
gage with, substantially as and for the pur-
pose set forth.

In testimony whereof I affix my signature in
presence of two witnesses.

JACOB FASNACHT.
